(57) **CLAIM**

The ornamental design for a clutch housing for pneumatic tool, as shown and described.

DESCRIPTION

FIG. 1 is a perspective view of a clutch housing for pneumatic tool of my design, showing in phantom other portions of a hand tool that are not a part of the present design;

FIG. 2 is an upper, right-front perspective view of the clutch housing for pneumatic tool shown in FIG. 1;

FIG. 3 is an upper, right-back perspective view of the clutch housing for pneumatic tool shown in FIG. 1;

FIG. 4 is a right side view of the clutch housing for pneumatic tool shown in FIG. 1, which due to symmetry is the same as the left side, top and bottom views of the clutch housing for pneumatic tool;

FIG. 5 is a front view of the clutch housing for pneumatic tool shown in FIG. 1; and,

FIG. 6 is a back view of the clutch housing for pneumatic tool shown in FIG. 1.
